ELECTRIC REGULATING SYSTEM

Friedrich Menzel, Stuttgart, Germany; vested in
the Alien Property CustodianOriginal application March 22, 1939, Serial No.
263,496. Divided and this application October
3, 1941, Serial No. 413,535. In Germany April
4, 1938

7 Claims. (Cl. 171—312)

This invention relates to an electric regulating system for electric generators, more particularly on vehicles, operating in parallel, of the type maintaining a substantially constant voltage until reaching a predetermined current intensity, and regulating the generator to a rapidly decreasing voltage as this predetermined current intensity is exceeded, the regulating for maintaining a substantially constant voltage and for causing a rapid decrease of the voltage being effected by a single electromagnetic regulator having a current coil which is influenced by an additional regulator hereinafter referred to as the "control governor."

This application is a division of my copending application Serial No. 263,496, filed March 22, 1939.

It has been found that the regulators of parallel operating light dynamos in most cases do not regulate their dynamos to exactly similar voltages. Hence, in case of any voltage differences, a return current is flowing from the dynamo producing higher voltage to the dynamo producing lower voltage and, consequently, the cut-out of the latter dynamo interrupts the circuit to the battery. However, under action of its voltage coil the cut-out is immediately closed again. As a result, the cut-out is opening and closing its contacts in rapid succession, whereby the contacts are heavily stressed and worn out prematurely.

It is an important object of the present invention to avoid such deleterious phenomena in parallel operating dynamos and to provide automatic means for equalizing their voltages.

With this and further objects in view, as may become apparent from the within disclosures, the invention consists not only in the structures herein pointed out and illustrated by the drawings, but includes further structures coming within the scope of what hereinafter may be claimed.

The character of the invention, however, may be best understood by reference to certain of its structural forms, as illustrated by the accompanying drawings in which:

Fig. 1 is a circuit diagram showing two light dynamos connected in parallel, including their regulators, having the invention applied thereto.

Fig. 2 is a circuit diagram similar to Fig. 1, but showing a modification thereof.

Similar characters of reference denote similar parts in the two figures, while the identical parts of the two parallel connected generator circuits are distinguished from each other by an index

added to the reference numeral of the lower circuit in each figure.

According to the invention, the regulators are so arranged that in case of a return current flowing from the dynamo producing higher voltage to the dynamo producing lower voltage, the control governor of the dynamo producing lower voltage influences the magnetisation of its associated regulator in a manner to produce an increased voltage in the associated dynamo.

Advantageously the control governor has a pair of electrically interconnected contacts, one of said contacts connecting the current coil of the regulator in case of return currents, for magnetizing the core of the regulator in a direction opposite to that of its associated voltage coil.

Referring now to the drawings in greater detail, and first to Fig. 1, it will be noted that each light dynamo 1 or 1', respectively, has a field coil 2 or 2', respectively, and a resistance 3 or 3', respectively, connected in series with its field coil. The storage battery is indicated at 4 and devices to be supplied with current are shown at 5, the battery 4 and the devices 5 making up the common consuming circuit.

Each dynamo has associated with it a regulator device, comprising two electromagnets each, indicated at 6 and 13, or 6' and 13', respectively. The electro-magnets 6 and 6' are centrally mounted in a U-shaped magnet frame 25 or 25', respectively, and are surrounded by a voltage coil 7 or 7', and a current coil 8 or 8'. The voltage coils 7 and 7' at their lower ends are connected to the ground, or to the body of the machine or vehicle, while the current coils 8 and 8' at their lower ends are electrically connected to their magnetic cores 6 or 6', respectively, as indicated. By means of leaf springs 20 and 26, or 20' and 26', two armatures 9 and 10 or 9' and 10' are suspended from the free ends of the outer legs of the magnet frames 25 and 25'. Provided on the downwardly directed leg of the angle-shaped armature 9 or 9' is a contact spring 28 or 28' carrying a contact 11 or 11' for cooperation with a contact 21 or 21'. Moreover, a contact spring 29 or 29' carrying two contacts 12 and 22, or 12' and 22', is mounted on the downwardly extending leg of the angle shaped armature 10 or 10'. The contact 12 or 12' is adapted to cooperate with a contact 23 or 23' while the contact 22 or 22' is provided for cooperation with a contact 24 or 24' of a U-shaped contact holder 33 or 33' interconnecting the contacts 23 and 24, or 23' and 24', and insulated from the mag-

net frame 25 or 25' on which it is mounted, by a layer of insulating material 34 or 34'.

The electromagnet core 13, or 13', together with an L-shaped magnet frame 30, or 30', forms a magnetic circuit which is energized by a voltage coil 14, or 14', the lower end of which is grounded, and a current coil 15, or 15'. Suspended from the free end of the L-member 30, or 30', by means of a leaf spring 31, or 31', is an angle-shaped armature 16, or 16', comprising a contact 17, or 17', at its depending arm, adapted for cooperation with a contact 27, or 27', which through a bracket 35, or 35' and an insulating layer 36, or 36', is mounted on the L-member 30, or 30'. The two magnetic frames 25 and 30, or 25' and 30', are insulated from the ground, or from the body of the machine or vehicle, respectively, and interconnected through a conductor 18, or 18'.

The members 9 and 9' constitute the armatures of the two cut-outs or charging switches, while members 10 and 10' constitute the armatures of the two control governors and members 16 and 16' constitute the armature of the two regulators. In the position of rest, as shown, the pairs of contacts 11, 21 or 11', 21', are open, while the pairs of contacts 22, 24, or 22', 24', and the contacts 17, 27, or 17', 27' are closed. Through the contacts 17, 27, or 17', 27', and parts 16, 31, 30, 18, 25, 8, or 16', 31', 30', 18', 25', 8', respectively, the field resistance 3, or 3', is short-circuited.

The operation of the arrangement shown in Fig. 1 is as follows:

As soon as the two dynamos 1 and 1', produce a sufficient voltage, the armatures 9 and 9' of the two cut-outs are attracted under action of their voltage coils 7 and 7', whereby the pairs of contacts 11, 21, and 11', 21' are closed. Moreover, the force of spring 26 is so related to the attraction exerted by core 6 that the pairs of contacts 22, 24 or 22', 24', respectively, are opened, without closing, however, the pairs of contacts 12, 23 or 12', 23'. With the tension of the two generators 1 and 1' rising, the armatures 16 and 16' of the two regulators are attracted under action of their voltage coils 14 or 14', with the result that the pairs of contacts 17, 27, or 17', 27' are opened and the short-circuit for the resistance 3, or 3', in the field circuit of the generator is interrupted. It follows that the resistance 3, or 3', is now introduced into the field circuit of the machine, in series with the field coil 2, whereby the excitation is weakened and the voltage of the generator is reduced. As the voltage reaches a predetermined lower value, the armature 16 is released and the field resistance 3 is again short-circuited, whereby the excitation of the generator is again augmented and its voltage is increased. These two actions are now alternating in rapid succession, after the manner of a vibration regulator, with the result that the voltage is maintained substantially constant until a given maximum intensity of current is reached.

The current coil 8, or 8', tends to increase the magnetisation of core 6, or 6', effected by the voltage coil 7, or 7'. As soon as the current supplied by the generator 1, or 1', reaches a predetermined intensity, the armature 10, or 10', of the control governor is attracted to such an extent as to close the contacts 12, 23, or 12', 23', thereby connecting the current coil 15, or 15', of the regulator 30, 13, or 30', 13', in parallel to the current coil 8, or 8', of the electromagnet 6, or 6'. The core 13, or 13', is now magnetised by

the current coil 15, or 15', in the same sense as by its voltage coil 14, or 14'. Consequently, the armature 16, or 16', is attracted, the connection between the contacts 17, 27, or 17', 27', is interrupted and the resistance 3 inserted in the field circuit, so that after reaching and exceeding the said predetermined current intensity, the regulator will regulate its generators to rapidly decreasing voltage. Since the current intensity is reduced by a decrease of the voltage, the armature 10, or 10' of the control governor is caused to oscillate to and fro, opening and closing the contacts 12, 23, or 12', 23' in rapid succession.

Now, assuming that the generator 1' regulates for a higher voltage than the generator 1, a current will flow from generator 1' to generator 1, through the conductors 37, 37, causing a return current through the current coil 8. Thus, the magnetisation of electromagnet 6 is weakened by such an amount that while armature 9 still remains attracted, retaining the contacts 11, 21 in their closed position, armature 10 is allowed to return into its position of rest, under action of its spring, thereby closing the contacts 22, 24. Consequently, the current coil 15 of the regulator is now also traversed by return current, through the members 33, 24, 22, 29, 10, 26, 25, 20, 9, 28, 11, 21, 37. As a result, the core 13 is now magnetised by current coil 15 in an opposite direction to voltage coil 14, whereby armature 16 is allowed to return to its position of rest, under action of its spring 31, closing the contacts 17, 27 and short-circuiting resistance 3, whereby the voltage of generator 1 is increased and equalised to that of generator 1'. Therefore, the return current flowing into the generator 1 is restricted to a low figure which is insufficient to cause opening of the contacts 11, 21 of the cut-out. Of course, if generator 1' is regulated to a lower voltage than generator 1, similar switching operations of the various relays of generator 1' will take place. Hence, the above mentioned undesirable opening and closing in rapid succession of the cut-out as a result of voltage differences between the two generators is prevented. Of course, if the return current is not due to such voltage differences between the two generators, the cut-out 11, 21, or 11', 21' will respond to it and break the connection of the generator with the consuming circuit. In other words, the return of armature 10 to its rest position precedes that of armature 9, but will not preclude interruption at 11, 21, if the closing of contacts 22, 24 fails to restore normal voltage conditions or at least to limit the return current through coil 8 to a small value which is insufficient to cause release of armature 9.

The circuit shown in Fig. 2 differs from Fig. 1 only as regards the contacts 23a, 24a, or 23'a, 24'a cooperating with contacts 12 and 22, or 12' and 22'. These contacts 23a, 24a and 23'a, 24'a unlike contacts 23, 24 and 23', 24', Fig. 1, are not interconnected by a common U-shaped holder, but the contacts 23, 23'a are connected to coils 15, 15', while contacts 24a, 24'a, are connected to separate voltage coils 32 or 32', respectively, which as shown are arranged to produce a magnetisation opposing that of voltage coils 14, 14', whereby the regulator in case of return current regulates for higher tension. The operation of this system otherwise is the same as described with reference to Fig. 1 and, therefore, will not require detailed explanation.

The method and apparatus of the present invention have been described in detail with refer-

ence to specific embodiments. It is to be understood, however, that the invention is not limited to the specific examples given, but is broader in scope and includes embodiments, other than those specifically described and illustrated in the drawings, such as are covered by the claims.

I claim:

1. In an electric circuit system, a common consuming circuit, two generators parallel connected to said common consuming circuit and, associated to each generator, first means adapted to make and break connection between their generator and said common consuming circuit and tending to prevent return currents from said consuming circuit by breaking said connection, second means adapted to regulate their generator for production of a substantially constant voltage until reaching a predetermined maximum current through said first means and further adapted to regulate their generator for production of a rapidly decreasing voltage as said maximum current is exceeded, and third means adapted to respond to the return currents flowing into their associated generator from the parallel generator, by influencing their associated second means in a manner to regulate their generator to an increased voltage, for precluding breaking action of said first means as a result of slight voltage differences between the two generators.

2. In an electric circuit system in vehicles, a common consuming circuit, two generators connected in parallel for feeding said common consuming circuit and, associated to each generator, first electromagnetic relay means adapted for making and breaking connection between their generator and said common consuming circuit under control of combined voltage and current windings tending to prevent return currents from said consuming circuit through said first relay means, second electromagnetic relay means adapted to regulate their generator for production of a substantially constant voltage up to a predetermined maximum current passing through said first relay, but to regulate for production of a rapidly decreasing voltage as said maximum current is exceeded, and third electromagnetic relay means adapted to respond to return currents passing through their first relay and to influence their second relay in a manner to regulate its generator to an increased voltage in case of such return currents.

3. In an electric circuit system in vehicles, a common consuming circuit, two generators connected in parallel for feeding said common consuming circuit and, associated to each generator, first electromagnetic relay means adapted for making and breaking connection between their generator and said common consuming circuit under control of combined voltage and current windings tending to prevent return currents from said consuming circuit through said first relay means, second electromagnetic relay means adapted to regulate their generator for production of a substantially constant voltage up to a predetermined maximum current passing through said first relay, but to regulate for production of a rapidly decreasing voltage as said maximum current is exceeded, and third electromagnetic relay means adapted to respond already to smaller return currents than their first relay and to influence their second relay in a manner to regulate its generator to an increased voltage already in case of such smaller return currents.

4. In an electric circuit system, a common

consuming circuit, two generators connected for parallel feed to said common consuming circuit, and, associated to each generator, an electromagnetic cut-out adapted for making and breaking connection between its generator and said common consuming circuit under control of a voltage coil and a current coil of said cut-out tending to prevent return currents from said consuming circuit into the generator, an electromagnetic regulator adapted to regulate its generator for production of a substantially constant voltage until reaching a predetermined maximum current passing through said cut-out, under action of a voltage coil of said regulator, and an electromagnetic control governor acted upon by a current coil and a voltage coil and adapted to switch in a current coil of said regulator as said predetermined maximum current is exceeded, whereby said regulator tends to regulate its generator to a rapidly decreasing voltage, said control governor moreover being adapted to switch in said regulator current coil in case of a return current passing through the current coil of the control governor, whereby said regulator current coil opposes its voltage coil and tends to regulate its generator to an increased voltage.

5. In an electric circuit system, a common consuming circuit, two generators connected for parallel feed to said common consuming circuit, and, associated to each generator, an electromagnetic cut-out adapted for making and breaking connection between its generator and said common consuming circuit under control of a voltage coil and a current coil of said cut-out tending to prevent return currents from said consuming circuit into the generator, an electromagnetic regulator adapted to regulate its generator for production of a substantially constant voltage until reaching a predetermined maximum current passing through said cut-out, under action of a voltage coil of said regulator, and an electromagnetic control governor acted upon by a current coil and a voltage coil and adapted to switch in a current coil of said regulator as said predetermined maximum current is exceeded, whereby said regulator tends to regulate its generator to a rapidly decreasing voltage, said control governor moreover being adapted to switch in an auxiliary coil of said regulator in case of a return current passing through the current coil of the control governor, whereby a magnetisation of the regulator core is produced opposing the magnetisation produced by its voltage coil and tending to release the armature of the regulator for increasing the voltage of the generator.

6. In an electric circuit system, a common consuming circuit, two generators parallel connected to said common consuming circuit and associated to each generator, first means adapted to make and break connection between their generator and said common consuming circuit and tending to prevent return currents from said consuming circuit by breaking said connection, second means adapted to regulate their generator for production of a substantially constant voltage until reaching a predetermined maximum current through said first means and further adapted to regulate their generator for production of a rapidly decreasing voltage as said maximum current is exceeded, said regulations being effected by selectively inserting and short-circuiting a resistance in the field circuit of the generator, and third means adapted to re-

spond to return currents flowing into their associated generator from the parallel generator, by influencing their associated second means in a manner to regulate their generator to an increased voltage, for precluding breaking action of said first means as a result of slight voltage differences between the two generators.

7. In an electric circuit system, a common consuming circuit, two generators connected for parallel feed to said common consuming circuit, and, associated to each generator, an electromagnetic cut-out adapted for making and breaking connection between its generator and said common consuming circuit under control of a voltage coil and a current coil of said cut-out tending to prevent return currents from said consuming circuit into the generator, an electromagnetic regulator adapted to regulate its generator for production of a substantially con-

stant voltage until reaching a predetermined maximum current passing through said cut-out, under action of a voltage coil of said regulator, and an electromagnetic control governor acted upon by said cut-out coils and adapted to switch in a current coil of said regulator as said predetermined maximum current is exceeded, whereby said regulator tends to regulate its generator to a rapidly decreasing voltage, said 10 control governor moreover being adapted to switch in an auxiliary coil of said regulator in case of a return current passing through the current coil of the cut-out, whereby a magnetisation of the regulator core is produced opposing the magnetisation produced by its voltage coil and tending to release the armature of the regulator for increasing the voltage of the generator.

FRIEDRICH MENZEL.
